(57) **CLAIM**

The ornamental design for a 3D printer desk, as shown and described.

DESCRIPTION

FIG. 1 is a front, left and top perspective view of a 3D printer desk, showing my design.

FIG. 2 is a rear, right and bottom perspective view thereof.

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

FIG. 9 is an enlarged view of detail 9 shown in FIG. 2; and, FIG. 10 is an enlarged view of detail 10 shown in FIG. 2. The broken lines in the drawings illustrate the portions of the 3D printer desk, which form no part of the claimed design.
